LATCH FOR GATES

Grady Johnson, Dayton, Ohio

Application May 29, 1959, Serial No. 816,747

3 Claims. (Cl. 292—87)

This invention relates to a latch particularly adapted for use with fence gates and the like.

In the usual arrangement of a gate in fencing, the gate is hingedly mounted on one of two spaced guide posts, and a retaining or latching device is provided between the gate and the other post for holding the gate in closed position. One well known type of such latching device includes a spring member which is secured at one end, usually to the gate or its frame, and having another or free end which is provided with a generally U-shaped, or similar, guide extending in spaced relation about the edge of the gate for limiting movement of the free end of the spring member to a direction toward and away from the edge of the gate. The spring member is stressed so as to be biased normally away from the gate into a locking or retaining position, and in this position, when the gate is closed, the free end of the gate member is received within a notch in a retainer which is suitably mounted upon the adjacent gate post. Obviously, under some circumstances it may be desirable to mount the retainer on the gate and the spring member on the post, or each on separate parts of a double gate, but in any event the interaction of these parts is the same, and when the retainer and spring member are aligned the spring member extends into the notch which prevents sidewise movement thereof and thus retains the gate against opening movement about its hinges.

When fencing employing a gate and latching device of the above described type is used, for example, to enclose a yard where small children are at play, or for some other type of enclosure in which it is desired to have the operation of the latching device require more positive action than mere bending or flexing of the spring member, the usual procedure is to use a separate chain about the gate frame and fence post, or some other separate means for locking the gate in closed position. The present invention relates to an improvement in such latching devices as above described, wherein the spring member is engaged in its retaining position in such a manner that deliberate positive action is necessary to disengage the spring member from the retainer notch. Furthermore, in combination with this improved latching device, provision is made for reception of a padlock or similar lock in the latching device which will lock the device in its engaged position to prevent unauthorized entry through the gate.

Accordingly, the primary object of this invention is to provide a latching device for gates and the like wherein the notched retainer member includes a pivotally mounted latch having a slotted free end which is movable partially across the retainer, such that the slot may receive or engage with an edge of the latch spring member to hold it within the retainer notch, and to require a twisting of the spring member along its length as well as a withdrawing movement thereof from the notch to release the spring member from the retainer.

Another object of the invention is to provide such an improved latching device wherein the latch and the re-

2

tainer are provided with cooperating apertures which are aligned when the slotted end of the latch is aligned with the retainer notch, providing for reception of a locking device through the aligned apertures and thus preventing withdrawal of the engaged spring member from the retainer.

A further object of this invention is to provide such a latching device which will not interfere with two-way opening of the gate when it is so hinged, and which may readily be adjusted to a non-operative position where it will be ineffective upon the latch spring member.

Other objects and advantages of the invention will be apparent from the following description, the accompanying drawings and the appended claims.

15 In the drawings—

Fig. 1 is a view of a typical section of fencing and gate in which latching devices of the character provided by the invention are incorporated;

Fig. 2 is a sectional view through the gate frame showing in plan the spring member and its guide mounted on the frame;

Fig. 3 is a view similar to Fig. 2 showing a retainer and latch mounted on the fence post;

Fig. 4 is a detail view, on a substantially enlarged scale, of the latching device provided by the invention;

Fig. 5 is a sectional view taken on line 5—5 of Fig. 4; and

Fig. 6 is a sectional view similar to Fig. 5, showing the spring member partially engaged with its retainer.

30 Referring to the drawing, which illustrates a preferred embodiment of the invention, Fig. 1 shows a typical application of the invention in which chain link fabric extends from opposite sides of stationary fence posts 10 and 12 to form a fence. A gate is provided between these 35 posts including a suitable frame 15 having fencing fabric stretched therewithin and mounted as by hinges 16, to swing about the post 10 relative to post 12. The gate and post 12 are provided with a latching device indicated by the general reference numeral 20 in Fig. 1, and including cooperating parts on the gate frame and the post which may engage, for example in the closed position of the gate, to retain the gate in a desired position.

Referring to Figs. 2, 3 and 4, the latching device includes a spring member 22 which is secured at its lower end 23 to the gate frame 15 by a suitable fastener 24, which may be for example a rivet, a self-tapping screw, or the like. As will be noted from the drawings, spring member 22 is of substantially greater width than thickness and extends away from the frame 15 and the secured lower end 23 such that the free upper end 25 of the spring member may be moved relative to the gate frame. The upper end 25 carries a generally U-shaped guide member 27 which is secured to the spring member in any suitable manner, and which extends around the gate frame 15 in spaced relation over most of its length, although portions of the free ends of guide member 27 may contact frame 15 slightly when the free end 25 of the spring member is positioned in its normally biased relation away from the gate frame. Thus, the guide member serves to locate the free end of the spring member for generally linear motion relative to the gate frame, although permitting some limited sidewise motion.

Cooperating with spring member 22, and mounted on the post 12, is a retainer 30 which fits around the post and is secured thereto by a half-round bracket 31 and suitable fasteners 32 at opposite ends thereof. The retainer 30 includes a generally rectangular notch 35 adapted for alignment with the free end 25 of spring member 22, and of sufficient width to receive the spring member. In normal position, with the gate closed, the spring member 22 extends into notch 35 and is free to move out of the notch only toward its open end, being

retained against any substantially sidewise movement, and thus retaining the gate in its closed position. However, as will be apparent from the drawings, it is a relatively simple matter to disengage this ordinary notch and spring relationship.

In accordance with the invention the retainer carries a latch 40 in the form of a curved arm pivotally mounted by a pin 42 on the retainer, to one side of the notch 35, and having a free end which may extend partially across the retainer notch. This free end of the latch is provided with a slot 45 adapted to engage about an edge of the spring member 22 when the latter is within notch 35, as shown particularly in Fig. 5. Latch 40 and retainer 30 preferably include cooperating apertures 47 and 48, respectively, through which a suitable locking device, for example a padlock (not shown) may be inserted to lock the spring member within notch 35. The mounting pin 42 also receives a retarding device in the form of a Belleville spring 50 which acts to bind against pivoting movement of the latch 40, and thus prevents its being swung open beyond a position where it will re-engage with spring member 22.

Assuming the parts to be in the position shown in Fig. 5, with the gate closed, it is impossible to withdraw member 22 from notch 35, against its normal bias, with a straight forward withdrawing movement, for example to the left as shown in Fig. 5, since the slotted end of the latch 40 is engaged around the free end 25 of the spring member and due to its pivotal mounting the latch member will cause the parts to bind against such withdrawing movement. However, if the spring member 22, or at least a substantial portion of free end 25 thereof, is twisted along its length, as by applying opposite forces to the arms of guide member 27, in the directions indicated by the arrows in Fig. 6, and the spring member is at the same time moved in the withdrawing direction, it may be freed from the retainer notch and latch member to permit opening of the gate.

In closing the gate, however, the spring member is withdrawn normally either manually or by camming action with the curved outer edge of retainer 30 and the gate moved in closing direction until the free end 25 of the spring member is aligned with notch 35. With the latch 40 moved outwardly toward the open end of notch 35, the open end of slot 45 will be in position to receive an edge of spring member 22, and when the spring member is free to move in its normally biased direction into notch 35 it will do so with latch 40 swinging normally inward and the slotted free end thereof passing about the edge of the spring member without interference with the closing action. This follows from the fact that the latch 40 is now pivoting inwardly toward notch 35 while the free end 25 of the spring member is moving in the same direction, tending to decrease the binding action therebetween.

As an example of a device constructed in accordance with the invention, in a retainer member having a spring member 22 with the width thereof (engageable in notch 35) of approximately one inch, and the notch accordingly of somewhat greater width to leave, for example, one-eighth inch clearance or slightly more, the pivotal latch member 40 has a slot 45 of approximately one-half inch or slightly greater depth, and the distance from the bottom of the slot to the pivot axis, i.e., to the pin 42 is about one and one-quarter inches. Obviously, the apertures 47 and 48 may be located wherever convenient.

The latch structure provided by the invention has been found most effective when the pivotal mounting of the retainer arm or latch 40 is located on that side of the enclosure surrounded by the fence, with the gate being hinged to swing inwardly or away from the latch 40. In this arrangement the spring member is easily twisted as it is withdrawn to enable the spring member to be disengaged from the retainer. On the other hand, it is considerably more difficult for a person standing on the other

side of the gate to reach across or over the gate, and in the configuration shown the twisting of the spring member is much easier to accomplish from the side of the gate opposite that on which the latch 40 is located. Obviously, however, the latch member provided by this invention is effective even without this preferred arrangement, and may be located on the other side where the circumstances so require.

Accordingly, the present invention provides a simple, easily constructed latching device for gates or the like which is effective to retain the gate in a predetermined position without use of additional retainers such as chains or other parts separate from the actual latching construction. The device provided by this invention is especially effective where fencing is employed to enclose a space for animals or to define a closed play area for small children, and the improved latching device effectively prevents these children from opening the gate, although it may be simply and quickly opened by an adult who understands the operation of the latching construction.

Furthermore, the latching device is easily adjusted for proper operation by rotation of retainer 30 on its post. In the event that the latch 40 should not be required for regular use, it may be rotated inwardly until it engages the post, leaving a freely open outer end of slot 35 in which the spring member 22 may engage in the usual manner.

While the form of apparatus herein described, constitutes a preferred embodiment of the invention, it is to be understood that the invention is not limited to this precise form of apparatus, and that changes may be made therein without departing from the scope of the invention as defined in the appended claims.

What is claimed is:

1. In a latch device for gates having an elongated relatively flat spring member mounted with a portion thereof movable for releasable engagement in a retainer to hold the gate in a desired position, the combination of a retainer having a notch formed therein of sufficient width to receive said portion of the spring member and to prevent sideways movement thereof, means on said retainer for mounting thereof in predetermined position for selective reception of said spring member in said notch, a latch pivotally mounted on said retainer and having a free end movable partially across said retainer notch, and said latch having a slot in said free end thereof adapted to engage with an edge of said spring member to hold it within said notch and requiring a twisting of said spring member along its length to free it from engagement with said notch and said slot for release of said spring member from said retainer.

2. In a latch device for gates having an elongated relatively flat spring member mounted with a portion thereof movable for releasable engagement in a retainer to hold the gate in a desired position, the combination of a retainer having a notch formed therein of sufficient width to receive said portion of the spring member and to prevent sideways movement thereof, means on said retainer for mounting thereof in predetermined position for selective reception of said spring member in said notch, a latch pivotally mounted on said retainer and having a free end movable partially across said retainer notch, said latch having a slot in said free end thereof adapted to engage with an edge of said spring member to hold it within said notch and requiring a twisting of said spring member along its length to free it from engagement with said notch and said slot for release of said spring member from said retainer, and said latch and said retainer having cooperating apertures therein adapted to be aligned in the engaged position of said latch to receive a locking device and effective to lock said latch in engaged relation with the spring member.

3. A latch for gates, comprising an elongated spring member adapted for mounting on the frame of a gate

with one end thereof free to move with respect to the gate frame and normally biased to a locking position away from the frame, guide means on said free end of said spring member extending in a direction to surround the gate frame in mounted position, a retainer adapted for mounting in stationary position on a gate post adjacent the gate frame and including a notch dimensioned to receive a portion of said free end of said spring member in the normal locking position thereof, a latch member pivotally mounted on said retainer to one side of said notch therein and having an end extending at least partially across said notch, said latch member having a slot in the end thereof over said retainer notch for engagement with one edge of said spring member in its

normal position to require a twisting movement of said spring member during withdrawal thereof from said retainer notch, and means resisting pivotal movement of said latch member to hold it adjacent said slot in the open non-latching position thereof.
